SHINGLE

Herbert Abraham, New York, N. Y., assignor to
 The Ruberoid Co., New York, N. Y., a corpora-
 tion of New Jersey

Application October 16, 1951, Serial No. 251,589

4 Claims. (Cl. 108—7)

1

This invention relates to improvements in a shingle, and more particularly to a shingle of the class commonly known as an interlocking asphalt shingle.

Among the objects and advantages of the invention are to provide shingles of this class:

(1) That can be laid selectively either to form a roof of single or of double coverage;

(2) That produce similarly shaped exposure patterns, though differing somewhat in dimensions, when laid in either manner. In the present instance the patterns are of hexagonal shape and attractive in appearance;

(3) That are self-aligning and easy to apply either for single or double coverage;

(4) That effect a firm interlock which is strongly resistant to winds of high velocity;

(5) That afford adequate nailing space to secure the shingles firmly when laid in either manner; and,

(6) That effect a marked economy in material for both single and double coverage use.

By the term "single-coverage" is meant a covering having only one thickness of roofing material at certain portions of the roof surface, and by the term "double-coverage" is meant a covering of at least two thicknesses of material at all portions of the surface. Single-coverage shingles are generally used for re-roofing purposes, that is, for application over previously shingled roofs, while double-coverage shingles are ordinarily used for new work. Provision of shingles that may be used for either purpose is advantageous, economical, and space-saving for the dealers since it permits them to keep in stock a single type of shingle to effect both manners of coverage. This is particularly true of the shingles of the present invention because, as hereinbefore stated when laid in either manner they produce hexagonal patterns, and accordingly satisfy the requirements of customers who desire roofs of either single or double coverage of that form.

In the accompanying drawings:

Fig. 1 is a top plan view of the improved shingle;

Fig. 2 is a plan view of several shingles laid to effect a covering that affords single-coverage; and,

Fig. 3 is a similar view of the shingles laid to provide a covering of double-coverage.

The shingle 10 is made of asphalt roofing material or the like and has sloping side edge portions 11—11 that slope downward toward the lower end or butt 12. The angularity of the edge portions 11 is that of the hypotenuse of a right-angle triangle whose base is one-half its altitude.

2

At each side of the butt is a locking tab 13 having a downwardly inclined upper edge 14 and a straight vertical outer edge 15.

The sides of the top or upper part of the shingle are defined by parallel vertical edge portions 16—16 and 18—18, respectively, the portions 16 and 18 at each side being joined by inclined edge portions 17. The edges 16 and 17 together form a shoulder 19 at each side. The top of the shingle has a straight horizontal edge 20.

As will hereinafter be more fully explained, the edge portions 16 and 18 provide guides for applying the shingles in proper alinement when laid either for single or double-coverage. For the sake of economy in material in cutting the shingles with the least waste, the inclination of the edges 17 is the same as that of the edges 14 of the locking tabs 13. The shingles are preferably cut from the sheet with alternate ones in reverse position in a manner well known in the art. With shingles of the present form, when so cut, the waste of material is somewhat less than one percent. The sheets from which shingles are cut are generally made in widths of about thirty-six or seventy-two inches, and accordingly the shingles are preferably cut so that each will have a height of eighteen inches.

Two slits 21 and 22 are formed in each inclined edge portion 11 of the shingle, the angularity of which slits is the same as that of said inclined edge portions. The provision of these slits enables the shingle to be laid with like shingles to effect either single or double coverage. The slits 21 are used when the shingles are laid for single-coverage while the slits 22 are used when they are laid for double-coverage.

To attain the desired results the location of the slits in the sides in an important feature. To obtain single-coverage with hexagonal shaped exposure patterns the end 23 of slits 21 must be so positioned that the vertical distance X from the lower end of the shingle to said end of the slit is equal to $\frac{1}{2}(H-h)$, where H is the height of the shingle and h is the minimum amount of headlap required to safeguard against leakage, and the vertical distance Y from the lower end of the shingle to the lower end 24 of slits 22 is equal to $\frac{1}{3}H$, that is, one-third the height of the shingle. For example, with a shingle of eighteen inch height intended to be laid for single-coverage with a two inch headlap the distance X will be eight inches, and the distance Y will be six inches.

In applying the shingles to provide a covering of single-coverage the locking tabs 13 of each

shingle A of an upper course are engaged in the slits 21 of two adjacent shingles B and C of the next lower course, as shown in Fig. 2, thus forming a succession of hexagonal exposure patterns in staggered arrangement throughout the roof. As laid for single-coverage the vertical edge portions 16 of the shingles in each course or horizontal row abut, thus providing a self-contained guide for properly and expeditiously laying the shingles in correct alignment. The shingles are secured to the roof by nails 25 driven into them above and adjacent to the slits 21 as illustrated.

To effect double-coverage, the shingles are laid as shown in Fig. 3. In this instance, the locking tabs 13 of each shingle A' are engaged in the slits 22 of shingles B' and C'. As so laid the shoulder portions 19 of adjacent shingles overlap and self-alignment is afforded by registering the edges 18 with each other. On referring again to Fig. 3 it will be seen that in this instance also the roof is formed of staggered hexagonal patterns.

It will be noted that when laid for single-coverage, as in Fig. 2, the ends 23 of the slits 21 of each pair of adjacent shingles of any course fall upon and line-up with the lower end or butt 12 of the shingle of the next upper course engaged in those slits, and that likewise when laid for double-coverage, as in Fig. 3, the ends 24 of the slits 22 register with the butt 12 of the overlapping shingle. In both instances the horizontal distance between the points 23-23 or 24-24, as the case may be, of adjacent shingles in a course is the same.

The preferred form of shingle, as herein noted, is eighteen inches high. It has a width of twenty inches at its widest portion between the side edges 16-16, a width of eighteen inches between the side edges 18-18, and a width of seven and one-half inches between the locking corners of the tabs 13-13, that is, between the points 35 where the upper edge 14 of the tab at either side meets the inclined side edge 11.

With shingles of the form, dimensions, and proportions described a "square" of roof surface, that is, an area of 100 square feet, may be covered for single-coverage with only about 167 square feet of shingle, and for double-coverage with about 249 square feet.

While I have referred to the openings 21 and 22 as "slits" I use the term in a broad sense to include slots or like openings designed to receive and interlock with the locking tabs in the manner described. The term "headlap" means the distance perpendicular to the butt edge that the butt of one shingle overlaps the head of another. The minimum headlap generally accepted in the roofing art is two inches. This has proven to be sufficient to prevent any water that may enter under the butt from leaking over the head of the underlying shingle.

Various modifications in detail may be made within the scope of the invention as herein described.

I claim:

5 1. A shingle adapted to be laid in interlocked relation with like shingles to form a covering of single-coverage or of double-coverage with hexagonal shaped exposure patterns in either case, said shingle having a single continuous downwardly sloping edge portions along each side, a locking tab at either side of its lower end, and two sets of slits formed in the sloping side edge portions one set spaced upward from the other, the lower set of slits providing means for interlocking to effect double-coverage and the upper set providing means for interlocking to effect single-coverage.

15 2. A shingle adapted to be laid in interlocked relation with like shingles to form a covering of single-coverage or of double-coverage with hexagonal shaped exposure patterns in either case, said shingle having a single continuous downwardly sloping edge portions along each side, a locking tab at either side of its lower end, the upper portion of the shingle immediately above the sloping edge portions being defined by a pair of parallel vertical side edge and a second pair of parallel vertical side edges offset inwardly from the first pair, the first mentioned vertical edges serving as guides for self-aligning the shingles when applied to effect single coverage and the second mentioned vertical edges as guides for self-aligning to effect double-coverage, and two sets of slits formed in the sloping side edge portions one set spaced upward from the other, the lower set of slits providing means for interlocking to effect double-coverage and the upper set providing means for interlocking to effect single-coverage.

30 3. A shingle as described in claim 1 in which the angularity of the sloping edge portions is that of the hypotenuse of a right-angle triangle whose base is one-half its altitude.

35 4. A shingle as described in claim 1 in which the lower end of each slit of the lower set is spaced vertically upward from the lower end of the shingle a distance equal to one-third the height of the shingle, and the lower end of each slit of the upper set is similarly spaced a distance equal to one-half of the remainder after subtracting the headlap from the height of the shingle.
